(57) **CLAIM**

The ornamental design for a nozzle for a rotary atomizer for a painting robot, as shown and described.

DESCRIPTION

FIG. 1 is a front view of a nozzle for a rotary atomizer for a painting robot;

FIG. 2 is a left side view of the nozzle;

FIG. 3 is a right side view of the nozzle;

FIG. 4 is rear view of the nozzle;

FIG. 5 is top view of the nozzle;

FIG. 6 is a bottom view of the nozzle; and,

FIG. 7 is a perspective view of the nozzle.
